CLAMPING MEANS FOR SLICING MACHINES

Eugene A. Ford, Scarsdale, N. Y., assignor, by
mesne assignments, to The Hobart Manufacturing
Company, Troy, Ohio, a corporation of
Ohio

Original application November 3, 1928, Serial No.
316,942. Divided and this application Septem-
ber 30, 1933, Serial No. 691,587

8 Claims. (Cl. 146—217)

This case is a division of my application Serial No. 316,942 for an improved slicing machine and is particularly directed to the novel clamping means of the machine.

5 Various other objects and advantages of my invention will be obvious from the following particular description of one form of mechanism embodying the invention or from an inspection of the accompanying drawings; and the invention also constitutes certain new and novel features of the construction and combination of parts hereinafter set forth and claimed.

In the drawings:

Fig. 1 is a top plan view of the machine;

15 Fig. 2 is a front elevational view of the machine, partly sectioned;

Fig. 3 is a side elevational view of the machine, partly sectioned;

20 Fig. 4 is a top detail view of the end clamp applied to the meat holder;

Fig. 5 is a detail side view partly sectioned of said end clamp; and

Fig. 6 is a section on line 6—6 of Fig. 2; and

25 Fig. 7 is a detail section through the cutting portion of the machine, showing the adjacent edge of the gage plate.

In detail, referring to Figs. 1, 2, and 3, the machine comprises a base 10 on which is supported a pair of vertical parallel standards 11 and 12. Secured to the top of the standards at the front end of the machine is a horizontally disposed plate 13. The standards 11 and 12 are provided on their outside surfaces near their upper edges with guide slots 14 and 15, respectively, cooperating with similar guide flanges 16 at each side of a horizontal plate 17 formed with a slot 18 open at the front and having two sides in the rear which are disposed at an angle to the aforesaid parallel flanges 16 rigid with the plate 17.

40 Riveted, or secured in any other desired manner to the top of plate 17 along the sides of the slot 18 is an open meat holder chute 19 having vertical sides 20 and 21 coincident with and extending upwardly from the sides of said slot 18. A vertically disposed post 22 is fixed to and between the plate 17 and a bracket 23 attached to the chute side 20. The lower portion 27 of the post is circular in cross-section while the upper portion 28 is cut away to provide flat parallel vertically disposed sides 29 for a purpose to be hereinafter made clear. A meat clamp support 30 is slidably mounted on the post by means of a collar 31 fitting over the post. The inside of 45 the collar is circular to fit the circular cross-

section of portion 27 of the post. By reference to Fig. 6 it will be seen that collar 31 has a slot 32 cut therein which is wide enough to permit the passage therethrough of the portion 28 of the post. When the clamp support is raised to its uppermost position and swung outwardly clockwise (as viewed in Fig. 6) until the sides of slot 32 are in line with the sides 29 of portion 28 of the post, the support may be slipped off the post, the slot 32 passing over the portion 28. 5 In a similar manner, the support may be slipped onto the post and by turning or lowering it slightly will be retained on the post. To manipulate the clamp, a handle 35 is revolubly journaled between the upper and lower plates 36 of the 10 clamp. Fixed to the handle for rotation therewith is the clamp proper provided with the toothed gripping plate 37. The clamp plate may be turned to any angle desired. Thus it may be disposed to grip a piece of meat resting against either plate 20 or 21 of the chute 19 or in the corner of the latter. In cutting a slab of bacon, the latter is placed with its long side against the plate 21 and is clamped thereto by plate 37 so that the knife will cut the bacon on a bias, providing an easy shearing cut. 15

The meat rests on top of a horizontal table 38 (Figs. 1, 3, 4, and 7) which is adjustable vertically to permit slices of different thicknesses to be cut from the bottom of the piece of meat by the knife blade 40 disposed at a slight angle to the horizontal. Fig. 7 illustrates how the distance between the knife edge of blade 40 and the edge of table 38 determines the thickness of the slice cut off. The depending extension 41 of table 38 guides the slice of meat as it is being cut. A pan may be placed on the base 10 to receive the meat when it drops from the knife. 20

The means for adjusting the height of table 38 comprises a hexagonal shaft 45 rotatably mounted between the standards 11 and 12 below the table. A pair of like cams 46 approximately spiral shaped are located at opposite ends of the shaft and fixed thereto. Each of a pair of parallel, like levers 47 extends to the right (as seen in Fig. 3) is pivoted intermediately and has its forward end engaging the cam surfaces of cams 46. The rear ends of levers 47 are provided with pins 48 seated in notches 49 of brackets 50 attached to the bottom of table 38 at the right end thereof. Similar levers 51, one at each side of the machine, extending to the left have their rear ends provided with pins 52 coating with slotted brackets at the left end of the table 38. The forward ends of the levers 51 rest on 25 30 35 40 45 50 55

like spiral cams 53 fixed to shaft 45. A spring 54 is fixed to each lower end of a pair of adjacent levers 47 and 51 urging the levers toward each other and into yielding engagement with 5 their respective cams.

Extending from plate 12 is a fixed hub 55 adapted to serve as a bearing for the shaft 45 and provided with an index mark 56 and a stop lug 57. The end of shaft 45 projects from hub 10 55 and has a knob 58 pinned thereto. The knob is provided with an index wheel 59 having numbers inscribed thereon representing different thicknesses of slice to be cut. To prevent the index wheel 59 being rotated past the zero point, 15 the wheel is provided with a lug 60 to abut stop 57 when in zero position.

The rotation of shaft 45 by means of knob 58 will turn cams 46 and 53 which through coaction with levers 47 and 51 will raise or lower the table 20 38 to provide for a thickness of slice shown on the index wheel 59.

To the right of standard 12, the base 10 carries a motor 65 for driving a flywheel 70 and an eccentric disk 71 rigid with the flywheel. An eccentric sleeve 73 embraces said disk 71 and is oscillated thereby. Arm 74 extending from the eccentric sleeve 73 is pivoted to the lower end of a lever 75 which has at its upper end a segmental rack 76 for cooperating with a rack 77 fixed to the 25 right hand end of a knife holder 78. The knife holder has disposed along its length a number of pins 79 which serve to locate and hold the knife blade 40 against displacement laterally. The blade similar to a safety razor blade may be lifted 30 off the pins to remove it from the holder. The previously mentioned top plate 13 mounted on standards 11 and 12 is provided with a guide slot 83 in which the knife holder 78 and knife blade 40 are located.

40 In operation, a piece of meat to be sliced is placed on the table 38 between clamp plate 37 and one of the walls 20 or 21 of the meat chute 19. The index wheel 59 is rotated until the desired thickness of slice to be cut is opposite the index mark 56. The table 38 is thereby adjusted to the necessary height relative to knife 40. The motor switch 100 (Fig. 2) is then turned on to start the motor which drives the gear 76. The latter coacts with rack 77 on the knife carrier 78 to rapidly and noiselessly reciprocate the knife blade 40 in its guides in the top plate 13. The operator with one hand grasps a handle 101 attached to the plate 17 at the right side thereof and beyond the adjacent flange 16 and with the other hand grasps the handle 35 of the meat clamp to keep the meat firmly in position in the meat chute. By pulling on the handle 101 the operator slides the meat chute and plate 17 on which it is fixed towards and past the knife which cuts a slice from the bottom of the piece of meat as it passes onto the top of plate 13. When the operator pushes the meat chute to the rear of the machine after a slice is cut off, the clamp 37 being slidably mounted on post 22, the meat held thereby is free to move downwardly until the bottom of the meat contacts table 38. The meat holder or chute is moved back and forth until the required number of slices are cut off.

To clamp the end piece of the meat a special 70 end clamp is provided comprising a horizontal pronged plate 105 (Figs. 4 and 5) and a vertical member 106 rigidly joined to the pronged plate. The member 106 has a vertical slot 107 therein fitting over the side plate 21 of the meat chute. The side plate 21 has fixed thereto a pair of

strips 108 forming between them a guide slot 109 for restraining the rear portion of member 106 to move vertically.

The end clamp holds the end piece of meat on table 38 and by actuation of handle 101, the meat is moved by the pronged plate 105 relative to the knife. The downward movement of the clamp is limited by the end of slot 107 engaging the top of plate 21.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A slicing machine comprising a knife, an article holder movable to and from the knife, and a clamp mounted on the holder for clamping the article in the holder, said clamp comprising a face plate, a guard plate extending at an angle to and in back of the face plate, a plate parallel to the guard plate fixed to the face plate, and a handle provided at one side of the guard plate and carried between the two parallel plates in back of the face plate, the guard plate being located between the handle and the knife during cutting of the article.

2. A slicing machine comprising a knife and means for feeding an article to and from the knife, said means including a chute open at both ends and an end clamp having a face plate extending at an angle to the sides of the chute and a supporting element rigidly fastened to one side of the face plate and extending over an edge of one side of the chute and provided with a slot 40 for receiving the said side of the chute, the movement of the end clamp being limited by contact of the closed end of said slot with the said edge of the chute.

3. The invention according to claim 2, in which the said side of the chute is provided with guide means for restraining the supporting element to slidable movement on the chute in a fixed path.

4. A slicing machine comprising a movable knife, a holder for carrying an article to the knife to be sliced, a clamp for engaging the article in the holder, a guide device on the holder extending transversely to the plane of the knife, a device on the clamp coacting with the guide device and movable therealong towards and away from the knife plane, one of aforesaid devices having a slot extending parallel to the direction of movement of the clamp and through which the other device may freely pass when aligned with the slot whereby the devices may be disengaged from each other by relative movement transverse to the direction of movement of the clamp.

5. In a slicing machine, a knife and means for holding an article to be sliced thereby comprising an article support, a clamp associated therewith, a carrier, a guide on the carrier and a coacting guide on the clamp for guiding the clamp to move towards said support, and one of said guides being slotted to permit the other guide to pass therethrough upon movement of the guides transversely to the direction along which the clamp moves towards the support, whereby the guides may be disconnected and the clamp removed from the carrier.

6. A slicing machine comprising a movable knife and means for carrying an article to the knife to be sliced thereby comprising a clamp for engaging the article, an underlying article support associated with the clamp, a guiding device for the clamp extending transversely to said support, a coacting guiding device on the clamp movable along the first-mentioned guiding device towards said support, one of aforesaid devices having a slot extending parallel to the direction of movement of the clamp and through which the other device may freely pass when alined with the slot whereby the devices may be disengaged from each other by relative movement transverse to aforesaid direction of movement of the clamp.

7. In a slicing machine, a knife, a gage plate generally parallel to the knife, a carriage, means for reciprocatingly mounting the carriage for movement across the gage plate and knife to cause the latter to cut a slice from an article in the carriage, a clamp for holding the article in the carriage, a guide on the carriage extending transversely to the gage plate, a portion on the clamp coacting with the guide for slidably mounting the clamp for movement towards the gage plate, said guide and said clamp portion being constructed with interlocking parts so arranged as to interlock with each other to prevent removal of the clamp from the guide except at the outer end of the travel of the clamp on the guide

and to there permit the clamp to be freely removed from the guide by movement transversely to the guide substantially parallel to the gage plate, and means on the carriage for preventing removal of the clamp from the outer end of the guide by movement longitudinally of the guide.

8. In a slicing machine, a knife, a gage plate generally parallel to the knife, a carriage, means for reciprocatingly mounting the carriage for movement across the gage plate and knife to cause the latter to cut a slice from an article in the carriage, a clamp for holding the article in the carriage, a guide rod on the carriage extending transversely to the gage plate, a portion on the clamp slidably and rotatably coacting with the guide rod to mount the carriage for movement towards the gage plate and for pivotal movement in a plane generally parallel to the gage plate, said guide rod and clamp portion being constructed with parts interlocking to prevent removal of the portion from the guide rod except when the clamp is swung to a predetermined position in which said parts release each other to permit removal of the clamp from the guide rod by movement transversely to the guide rod, and means preventing removal of the clamp from the guide rod by movement of the clamp longitudinally of the guide rod.

EUGENE A. FORD. 30
